CLAIM

The ornamental design for a stand for an electronic photo booth as shown and described.

DESCRIPTION

1. Stand for electronic photo booth
Fig. 1.1 is a front view of a stand for electronic photo booth in accordance with the present design;
Fig. 1.2 is a rear view of the stand for electronic photo booth of Fig. 1.1;
Fig. 1.3 is a right side view of the stand for electronic photo booth of Fig. 1.1;
Fig. 1.4 is a left side view of the stand for electronic photo booth of Fig. 1.1;
Fig. 1.5 is a top view of the stand for electronic photo booth of Fig. 1.1;
Fig. 1.6 is a bottom view of the stand for electronic photo booth of Fig. 1.1;
Fig. 1.7 is a top right rear perspective view of the stand for electronic photo booth of Fig. 1.1;
(Continued)

(Continued)

Fig. 1.8 is a top left rear perspective view of the stand for electronic photo booth of Fig. 1.1;
 Fig. 1.9 is a top right front perspective view of the stand for electronic photo booth of Fig. 1.1; and
 Fig. 1.10 is a top left front perspective view of the stand for electronic photo booth of Fig. 1.1.
